ATTORNEY

UNITED STATES PATENT OFFICE

BENJAMIN GORDON, OF PHILADELPHIA, PENNSYLVANIA

TOY

Application filed March 23, 1928. Serial No. 264,200.

This invention relates to a device in the form of a toy adapted to be used by children to obtain the pleasurable benefits of a teeter.

The principal object of the invention is the production of a device of the indicated character which will embody improvements by virtue of which the device may be manufactured at a comparatively low cost, so that the seat and foot rest thereof will be readily adjustable to accommodate children of different sizes; and so that the device will be more sturdy and durable in use.

The nature of the invention and its distinguishing features and advantages will appear when the following specification is read in connection with the accompanying drawing, in which—

Figure 1 is a perspective view of the preferred form of the device.

Fig. 2 is a sectional view taken on the line 2—2 of Fig. 1.

Fig. 3 is a side view of the seat and parts connected therewith.

Fig. 4 is a sectional view taken on the line 4—4 of Fig. 1.

Fig. 5 is a perspective view of the device illustrating certain modifications.

Figs. 6, 7 and 8 respectively are detail sectional views taken on the lines 6—6, 7—7 and 8—8 of Fig. 5.

Referring now more particularly to Figs. 1 to 4 inclusive of the drawing, it will be apparent that the preferred form of the device includes a structure produced from a single piece of cross sectionally round steel, bent and formed to provide a base 10, a support 11, and spring coils 12 connecting the support 11 with the base 10 so that the support 11 will be normally but yieldingly disposed at an angle with respect to the base 10. The base 10 is of U-shape, there being a coil 12 at one end of each of the longitudinal members 13 thereof, which coils rest on the floor adding to the support action of the base 10 and the support 11 consists of members 14 extending respectively from the coils 12, each being bent in its length to provide a lateral portion 15, longitudinal portion 16, and a lateral end portion 17. It will thus be apparent that the support 11 is connected at one end with the

base 10 and inclined upwardly over the base 10.

Arranged on the free end of the support 11 is a seat 18 having an upstanding member 19, the latter being cut out in simulation of the head of an object, the same being a horse's head in the present instance which may be appropriately painted. The member 19 has handles 20 which respectively extend laterally from opposite sides thereof. The seat 18 rests in part on the portion 16, and also rests on the end portions 17. The member 19 is connected with the seat 18 and both are connected for adjustment with respect to the support 11 by a suitable means, which consists of lugs 21 on the member 19 which respectively extend through slots in the seat 18 and embrace the portions 16, there being a bolt 22 which extends through the lugs 21 below the portion 16, and a nut 23 applied to the bolt 22 serves to effectively clamp the parts in place. A foot rest 24 is connected with the portions 16 of the support 11 below the seat 18. This is accomplished by the provision of a strap 25 which embraces the portions 16 and is secured to the foot rest 24, as at 26.

The main structure of the device may be diversely formulated to produce the desired results. For instance, as shown in Fig. 5, the main structure includes a base 27 of tubular material bent into a U-shape to provide longitudinal members 28 and a connecting member 29. A single piece of spring steel is formed to provide a spring coil 30, a comparatively short member 31 and a comparatively long member 32 which constitutes a support. The member 31 is rigidly connected with the connecting member 29 by a suitable fastening element such as the rivet 33. The seat 34, similar to the seat 18, and member 35 similar to the member 19 are rigidly connected with the member 32 by a suitable fastening element such as a bolt 36 which extends through lugs 37 and the member 32, there being a nut 38 on the bolt 36. The lugs 37 are connected with the member 35 and extend respectively through slots in the seat 34. A foot rest 39 is adjustably mounted on the member 32, and this is accomplished by providing clamping means 40 on the under side of the foot rest 39.

which may be slipped on the member 32. The foot rest 39 will therefore be adjustable on the member 32 with respect to the seat 34.

From the foregoing it will be apparent that 5 a child may be seated on the seat of the device with both feet resting on the foot rest thereof and may grip the handles. The child by exerting himself or herself may move up and down after the manner of a teeter; the support 11 of the preferred form of the device and the support 32 of the modified form, reacting to cause upward movement after each downward movement under the weight of the child.

15 It will also be apparent in connection with the preferred form of the device shown in Fig. 1, that the portions 15 may serve as foot rests in which case the foot rest 24 will be omitted; the seat 18 being adjustable on the support 11 relatively to the portions 15 to accommodate children of different sizes.

I claim:

1. A device of the class described comprising a main structure formed of a single piece 25 of material providing a U-shape base section, a support having lateral portions, and spring coils, said coils connecting the base section with the support, said support being normally but yieldingly disposed at an angle over 30 the base section; said coils and base section constituting points of support for the entire device and a seat on the free end of the support resting on the lateral portions.

2. A device of the class described comprising 35 a base on which the device rests, a support, spring coils connecting one end of the support with one end of the base with the support normally but yieldingly disposed at an angle with respect to the base, a seat having 40 an upstanding member, said base and spring coils constituting points of support for the entire device, said seat being secured to the free end of the support, handles respectively extending laterally from opposite sides 45 of the upstanding member, and a foot rest secured to the support below the seat.

3. A device of the class described comprising 50 a structure formed of a single piece of spring metal to provide a U-shape base section for the device, a support having lateral portions constituting foot rests, and spring coils connecting the base section with the support, said support being normally but yieldingly disposed over the base section; said base 55 section and spring coils constituting supports for the entire device and a seat having handles connected therewith adjustably mounted on the free end of the support.

4. A device of the class described comprising 60 a single piece of material bent upon itself to form a cross member and side members connected therewith to provide a base section, said material being coiled to provide a spring on one end of each side member, said material 65 being extended from each coil to provide a

supporting member bent laterally to an intermediate point, to provide a foot rest, and also bent laterally at its end to provide a seat support, each supporting member being normally but yieldingly disposed at an angle 70 with respect to the base section, a seat resting on said supporting members with the lateral ends thereof in contact with the under side of the seat, and a clip which secures said seat to said supporting members, and which also 75 secures the supporting members together.

Signed at Phila., in the county of Phila., and State of Penna., this March 21, 1928.

BENJAMIN GORDON.
